No. 668,165.

Patented Feb. 19, 1901.

W. COLLIGAN.

LIQUID COOLER.

(Application filed May 31, 1900.)

(No Model.)

UNITED STATES PATENT OFFICE.

WILLIAM COLLIGAN, OF WATERBURY, CONNECTICUT.

LIQUID-COOLER.

SPECIFICATION forming part of Letters Patent No. 668,165, dated February 19, 1901.

Application filed May 31, 1900. Serial No. 18,666. (No model.)

To all whom it may concern:

Be it known that I, WILLIAM COLLIGAN, a citizen of the United States, residing at Waterbury, in the county of New Haven and State of Connecticut, have invented certain new and useful Improvements in Liquid-Coolers; and I do declare the following to be a full, clear, and exact description of the invention, such as will enable others skilled in the art to which it appertains to make and use the same.

My invention relates to that class of liquid-coolers which are designed to hold only a limited amount of liquid which is cooled by means of contact with the chilled surfaces of the chambers through which it is made to pass between the point of inlet and the point of outlet.

The object of my invention is to produce a cooler of the class above mentioned which is more simple in construction than those now in use, more easily taken apart and cleaned, and more cheaply manufactured, having a lengthy liquid course and few parts. I attain this object by means of the mechanism illustrated in the accompanying drawings, in which—

Figure 1 is a side elevation of my improved cooler ready for use; Fig. 2, a side elevation of the rod used to connect together the several parts; Fig. 3, a ground plan of the bottom; Fig. 4, a sectional view of same on line $x x'$; Fig. 5, a ground plan of the cover or top; Fig. 6, a sectional view on line $y y'$; Fig. 5, of the connection-screw used for inlet and outlet of the liquid, showing the manner in which it is connected with the cover or top; Fig. 7, a ground plan of one of the chamber-sections which constitute the liquid course; Fig. 8, an elevation of the same, and Fig. 9, a perspective view of the washer used between the ends of the liquid-course chamber-sections and the top and bottom.

Similar figures refer to similar parts throughout the several views.

The body of this device is made up of the chamber-sections 1, composed of metal, glass, or any suitable non-corrosive substance, provided with the projecting shoulders 2 at each end, which are used as bearings for the washers 3, which are used to prevent leakage between the ends of the chamber-sections and the top and bottom. For the purpose of de-

scribing my invention I use four of these chamber-sections, but more may be used if it is desired to lengthen the liquid course or 55 fewer if it is desired to shorten it. I do not confine myself to the shape of these chamber-sections here shown, as the device would work equally well with chamber-sections of a different shape with suitable modifications in the 60 other parts to correspond to the same. The saucer-shaped bottoms (shown by Figs. 3 and 4) are provided with cross-bars or partitions 4, 5, 6, and 7, so arranged as to receive the ends of the chamber-sections and to divide the inside 65 of the bottom into as many recesses as there are chamber-sections or partitions, 4 and 6 being partially cut away at 8 and 9, respectively, to form passways between the recesses in the bottom. The top or cover (shown in 70 Figs. 1 and 5 in its inverted-saucer-like form) is similarly provided with cross-bars or partitions 10, 11, 12, and 13, which in like manner divide the inside of the top into as many recesses as there are chamber-sections. The 75 bar 11 is partially cut away to form a passway similar to 8 and 9.

The top or cover is provided with metal connection-screws 14 and 15, so arranged that the metal of which the top or cover is cast (shown 80 by 16) incloses the flange of the screw and securely holds it, forming a passage (shown by 17) for inlet and outlet purposes in such a way as to prevent contact with the metal of which the screw is composed. This is desirable, as the metal of which the screw is composed is chosen with a view only to its being 85 strong and tough, while the metal composing the top or cover, as well as all the metal or other material which comes in contact with 90 the liquid, is chosen with a view to its non-corrosive qualities. The metal of the top or cover is so cast in and around the connection-screws that suitable holes 18 and 24 are provided for inlet and outlet purposes. 95

The bottom at 19 and the top or cover at 20 are each suitably depressed at their centers toward their open ends for the purpose of providing convenient spaces to receive the head 21 and nut 22 of the bolt or rod which holds 100 the device together.

The washer above referred to is pierced out at 23 to receive the ends of the chamber-sections, the holes 23 corresponding in size to

the transverse sectional shape of the chamber-sections.

When all the parts are put together and are ready for operation, as shown by Fig. 1, the 5 bar 13 of the cover is directly over (with sections intervening) the bar 7 of the bottom. In like manner 10 is over 4, 11 over 5, and 12 over 6.

In operation the course of the liquid is as 10 follows: Introduced into the hole 24 from a supply-pipe suitably connected therewith it flows down into the chamber of the section directly beneath the inlet 24, thence through the passage 8 in the cross-bar 4 of the bottom 15 and up into the chamber between the bars 10 and 11, thence through the passage in the bar 11 of the top and down into the chamber between bars 11 and 12, thence through the passage 9 in the cross-bar 6 of the bottom and 20 up into the chamber between the bars 12 and 13, thence out through the outlet 17, to which outlet there may be attached an ordinary draw-faucet.

If desired, the course may be reversed, using 25 17 for an inlet and 24 for the outlet, in which event the positions of the supply-pipe and draw-faucet are reversed. I do not wish to confine the location of the inlet and outlet holes to the top or cover, as the same results 30 may be obtained by locating them in the chamber-sections directly beneath their present location, as shown in dotted lines at 25 and 26.

Having thus fully described my invention, 35 what I claim, and desire to secure by Letters Patent, is—

1. A liquid-cooler comprising a number of chamber-sections 1 provided with means for connecting them with the coöperating parts

of the cooler; a bottom, the inside of which 4c is provided with a number of recesses equal in number to the number of chamber-sections the partitions between which recesses are alternately partially cut away to form liquid-passways; a top or cover recessed similarly to 4f the bottom, and having a sufficient number of its partitions partially cut away to complete the liquid course, provided with inlet and outlet holes, and means for connecting therewith a supply-pipe and draw-faucet; washers 3 between the cross-bars or partitions of the top and bottom and the projecting shoulders 2 of the section-chambers; and means (bolt and nut) for securing together all of the foregoing parts substantially as described. 5c

2. A liquid-cooler comprising a number of chamber-sections 1 provided with means for connecting them with the coöperating parts of the cooler, two of said sections being each provided with a hole for inlet and outlet purposes; a bottom, the inside of which is provided with a number of recesses equal in number to the number of chamber-sections, the partitions between which recesses are alternately partially cut away to form liquid-passways; a top or cover recessed similarly to the bottom, and having a sufficient number of its partitions partially cut away to complete the liquid course; washers 3 between the partitions and the projecting shoulders 2 of 6c the section-chambers; and means (bolt and nut) for securing together all of the foregoing parts substantially as described. 7c

WILLIAM COLLIGAN.
